L. C. MYERS
TYPEWRITING MACHINE

1,751,840

Filed Jan. 14, 1927

UNITED STATES PATENT OFFICE

LEWIS C. MYERS, OF FREEPORT, NEW YORK, ASSIGNEE TO ROYAL TYPEWRITER COMPANY, INC., OF NEW YORK, N. Y., A CORPORATION OF NEW YORK

TYPEWRITING MACHINE

Application filed January 14, 1927. Serial No. 161,113.

This invention relates to means for registering the amount of work performed on a typewriting machine and comprises broadly a counter or cyclometer of any old or desired type having a shaft which is geared to the escapement shaft or escapement wheel of the typewriting machine in such a way that it is operated step-by-step only during the forward step-by-step movement of the carriage brought about by a depression of the type keys or space key.

Such a construction obviates objections inherent in the usual word counting devices in which the counters could be actuated by a simple depression of the space key and in which a word of two or three letters counted the same as a much longer word since the counter was actuated only by the space key following the writing of the word. Moreover, in practically all such constructions the counter is actuated either by the space key or type keys and additional work is placed upon these keys, making the touch heavier. In such cases, it was always easy for the operator to determine how much work was registered on the machine and different operators could compare the amount of work without difficulty. In the counting device constructed in accordance with the present invention, the counter may be arranged to operate at different ratios so that one unit of the counter may indicate anything from the printing of one letter up to perhaps the printing of 200 letters or spaces. It is always an easy matter to arrange different machines so that the counting device operates at different ratios, thus rendering it impossible or difficult for the operators to compare their work.

Devices of this character have previously been employed but it is the purpose of this invention to provide a support for the counter and its connection to the escapement mechanism which is simple and yet strong and which can be attached readily to the typewriting machine without the necessity of making any change whatever in the construction of the machine itself. The invention is illustrated as applied to the Royal typewriter, but with minor changes it may be applied to other types of machines.

In the drawings:

Figure 1 is a side elevation of a portion of a typewriting machine showing the invention applied thereto.

Figure 2 is a front view of the same.

Figure 3 is a top plan view.

Figure 4 is a top plan view of the main supporting plate.

Figure 5 is a top plan view of an adjustable plate mounted on the main supporting plate.

Figure 6 is a bottom plan view of a holder for the counter adjustably mounted on the main supporting plate.

The drawings disclose a portion A of the main frame of the machine along which travels a carriage B having a platen C against the front of which strike type bars D. To the main frame is attached a casting E which supports the escapement mechanism. At its upper side this casting is provided with an antifriction roller e which bears against the under side of a rail F carried by the carriage. Another antifriction roller e' is attached to the casting and bears against the opposite side of the rail F. The escapement shaft has a pinion G with which meshes the rack bar H of the carriage and mounted on said shaft is the usual escapement wheel I with which cooperate the escapement dogs (not shown).

A pawl K is carried by one side of the escapement wheel and is pressed into engagement with the pinion G by means of a spring k. This causes the escapement wheel and pinion to turn together in one direction but permits the pinion to rotate in the opposite direction independent of the escapement wheel. The usual carriage stop stud L is indicated in the drawings and the usual bell hammer arm M which is pivotally carried by a bracket N attached to the casting E, which arm is normally urged in one direction by a spring O. As illustrated these parts are thus used in the usual Royal machine, but so far as the invention is concerned they may be varied in construction.

The main supporting plate 1 shown in plan view in Figure 4 is formed of sheet metal and has a downwardly bent ear 2 which is 100

fastened to the casting E by a screw 3 already present in the machine. The supporting plate 1 also has an upwardly extending arm 4 which has riveted thereto a bushing 5 containing a set screw 6. The bushing 5 and arm 4 fit over the end of the carriage stop stud L and are held in position by tightening the set screw 6. In this manner the device is firmly held in position but may be quickly removed if desired. Its application involves no change whatever in the usual construction of the machine. The main supporting plate 1 is provided with two screw threaded holes 7 and 8 and near its outer end with two elongated slots 9 and 10, the purpose of which will be hereinafter set forth.

The adjustable plate 11 shown in plan view in Figure 5 lies on top of the main plate 1 and is provided with an elongated slot 12 near one end through which passes a screw 13 which threads into the opening 7 on the main plate 1. Near its other end the auxiliary plate 11 has an elongated slot 14 through which passes a screw 13' which threads into the opening 8 of the main plate 1.

The auxiliary plate has at its ends upturned ears 15 and 16, each provided with an opening and these ears serve as supports for the operating shaft 17. At one end this shaft is provided with a star or ratchet wheel 18 which engages with and is operated by the escapement wheel I. At the other end the shaft 17 is provided with a small gear or pinion 19 which meshes with a larger pinion 20 on the main shaft of the counting device 21.

This counting device may be of any usual or desired character and is supported in position in the following manner.

A sheet metal member 22 shown in plan view in Figure 6 is held in position upon the main supporting plate 1 by means of a screw 23 which passes through the slot 9 in the main plate and engages a screw threaded opening 24 in an ear of the member 22. This member 22 is provided with flanges at its edges which are bent upwardly and inwardly at 26 to fit over the base 25 of the counter 21. A screw 27 passes through the slot 10 in the main supporting plate 1 and through a threaded opening 28 in the member 22 and bears against the under side of the base 25 of the counting device, thus holding the same in position because of the pressure between the flanges 26 and the base, a lock nut 27' also being provided.

It will be noted that the main plate is bent to form an open space 29 and the auxiliary plate is similarly bent to form an open space 30, but this is merely to permit proper operation of the bell hammer M without interference with said plates.

It is noted that the main plate 1 is rigidly fixed in position but the auxiliary plate 11 is adjustably mounted upon the main plate. This adjustment is permitted by means of the

slots 12 and 14 in said auxiliary plate. This adjustment is desirable for two purposes. In the first place, different size ratchet wheels are employed in the escapement mechanism, some of which have twelve teeth and others ten and it is, therefore, necessary to vary the position of the ratchet or star wheel 18 with reference to the escapement wheel when a change is made in the latter. In order to prevent interference of the shaft 17 with the center stop pivot screw, not shown and the bell hammer arm which are in the machine, it is found desirable to make the plate adjustable at both ends.

The member 22 which carries the counter is also made adjustable on the main plate since whenever it is desired to change the ratio, it is necessary to change the pinion 19 or the gear 20 or both. The flanges 26 which engage the base 25 of the counter will permit the counter to be adjusted endwise in order that the gear 21 may be placed in the same plane with the pinion 19.

It will be obvious that the invention comprises an attachment which is strong and rigidly supported upon the frame of the machine in a very simple manner and without interference with any of the existing parts of the machine. The various adjustments provide simple and efficient means for permitting escapement wheels of different sizes to be used and permitting the ratio to be changed without any difficulty. The counter may also be readily removed if desired for any purpose without interfering with any of the other parts. If it is desired to remove the whole attachment, this can be done quickly and without necessitating any change of adjustment of the remainder of the machine. It is obvious that various detail changes can be made in the precise embodiment of the invention without in any way departing from the spirit of the same, which is to be regarded as limited only by the scope of the appended claims.

I claim as my invention :

1. In a counter attachment for typewriting machines having a supporting frame, an escapement wheel, a bracket attached rigidly to the frame, and a counter mounted on the bracket and including a driving gear therefor, the combination of means for transmitting motion from the escapement wheel to the driving gear comprising a plate and driving means mounted on the plate for cooperation with the escapement wheel and the driving gear of the counter, and means for mounting the plate together with the driving means on the bracket for bodily adjustment in a plane substantially at right angles to the axes of the escapement wheel and the driving gear.

2. In a counter attachment for typewriting machines having a supporting frame, an escapement wheel, a bracket attached rigidly to the frame, and a counter mounted on the

bracket for adjustment in a plane substantially at right angles to the axis of the escapement wheel, said counter including a driving gear therefor, the combination of means for transmitting motion from the escapement wheel to the driving gear comprising a plate and driving means mounted on the plate for cooperation with the escapement wheel and the driving gear of the counter, and means for mounting the plate together with the driving means on the bracket for adjustment in a plane substantially at right angles to the axes of the escapement wheel and the driving gear.

3. In a counter attachment for typewriting machines having a supporting frame, an escapement wheel, a bracket attached rigidly to the frame, and a counter mounted on the bracket and including a driving gear therefor, the combination of means for transmitting motion from the escapement wheel to the driving gear comprising a plate and driving means mounted on the plate for cooperation with the escapement wheel and the driving gear of the counter, and means at each end of the plate for independently adjusting said plate together with the driving means on the bracket in a plane substantially at right angles to the axes of the escapement wheel and the driving gear.

4. In a counter attachment for typewriting machines having a supporting frame, an escapement wheel, a bracket attached rigidly to the frame, and a counter mounted on the bracket for adjustment in a plane substantially at right angles to the axis of the escapement wheel, said counter including a driving gear therefor, the combination of means for transmitting motion from the escapement wheel to the driving gear comprising a plate and driving means mounted on the plate for cooperation with the escapement wheel and the driving gear of the counter, and means at each end of the plate for independently adjusting said plate together with the driving means on the bracket in a plane substantially at right angles to the axes of the escapement wheel and the driving gear.

In testimony whereof, I have hereunto subscribed my name.

LEWIS C. MYERS.
